Primary Examiner — S. Bryan Reinholdt, Jr.*Assistant Examiner* — Kyle A. Edelmaier(57) **CLAIM**

The ornamental design for a circulation fan as shown and described.

DESCRIPTION

FIG. 1 is a front, right, and top perspective view of the circulation fan, showing my design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the circulation fan that form no part of the claimed design.
